UNITED STATES PATENT OFFICE

PETER E. GELDHOF, OF SYRACUSE, NEW YORK, ASSIGNOR TO SYRACUSE WASHING MACHINE CORPORATION, OF SYRACUSE, NEW YORK, A CORPORATION OF DELAWARE

CENTRIFUGAL CLOTHES DRIER

Application filed October 19, 1926. Serial No. 142,594.

This invention relates to a centrifugal clothes drier of the motor driven type in which the clothes container is rotatably mounted within a suitable casing having a movable cover upon which an electric motor is mounted and operatively connected to the container for rotating the same and thereby expelling the moisture from the clothes by centrifugal force.

10 These machines are preferably used in connection with clothes washing and rinsing vats in such manner that the wet clothes from the vat may be drawn therefrom by hand and deposited directly into the rotary container or 15 they may be withdrawn by hand from the container and deposited directly into the same or any other vat or receptacle without dripping of the water from the clothes on to the floor.

20 Heretofore one of the most serious objections to the use of rotary centrifugal containers of this type has been the excessive vibration produced by excessive mass weight of the clothes eccentric to the axis of rotation and in order to reduce this excessive vibration it has been necessary to arrange 25 the clothes by hand so as to distribute the mass weight more evenly around said axis.

Furthermore, as heretofore practiced it 30 has been deemed necessary to make the rotary container of considerably greater diameter than vertical height so as to obtain the desired capacity and centrifugal throw of the water from the clothes but it is, of course, 35 obvious that the vibration of the machine due to the unbalancing of the load therein, increases with the increased diameter of the container thereby aggravating the objection above referred to.

40 One of the specific objects of the present invention is to construct and support the rotary container in such manner that the clothes may be deposited promiscuously therein without regard to the balancing of the mass by 45 redistribution and without producing excessive vibration of the machine and at the same time to expedite the drying operation and thereby greatly increase the out-put of the work for a given period of time.

50 In other words, I have sought to avoid the

excessive vibration by reducing the diameter and increasing the vertical depth of the container whereby the mass of clothes when promiscuously arranged therein will be brought closer to the axis of rotation while the increased vertical depth maintains the desired capacity, it being understood that the closer the mass is brought to said axis the less will be the vibration of the machine during the rotation of the container.

55 Another object is to support the container upon vertically spaced journal bearings which maintain their co-axiality with each other and with the axis of the container as the latter is rotated and at the same time to maintain an unobstructed interior capacity 60 throughout the entire interior height and diameter of the container for the free distribution of the clothes therein and expression of the water therefrom by centrifugal 65 force.

Another object is to mount the entire power plant including the motor and driving connections between the motor and container upon the cover for the casing so as to move 70 with the cover as the latter is opened and closed.

75 A further object is to operate the motor controlling switch and a suitable brake mechanism by one and the same operating member whereby one movement of said member in one direction will release the brake and simultaneously close the motor switch while another movement of the same member will cause the switch to open and simultaneously apply the brake for stopping the 80 motor and container driven thereby.

85 Other objects and uses relating to specific parts of the invention will be brought out in the following description.

90 In the drawings:
Figure 1 is a top plan of a centrifugal clothes drier embodying the various features of the invention showing adjacent portions of the washing machine to which the centrifugal 95 drier is attached, a portion of the gear case between the motor and container being broken away and the cover therefor removed.

Figure 2 is an enlarged detail sectional view 100 taken on line 2-2, Figure 1, showing more

particularly the construction of the motor controlling switch and its operating mechanism.

Figure 3 is an enlarged detail sectional view taken on line 3-3, Figure 1, showing more particularly the brake mechanism.

Figure 4 is a longitudinal vertical sectional view of the apparatus taken on line 4-4, Figure 1.

10 Figure 5 is a top plan of a modified construction of centrifugal drier in which the motor is mounted in a vertical position on the cover.

15 Figures 6 and 7 are enlarged detail sectional views taken on lines 6-6 and 7-7, respectively, Figure 5, the lower portion of the container and its inclosing case being broken away.

10 The apparatus shown in Figures 1 to 4 inclusive comprises a horizontal base section 1 supported at any convenient height by one or more legs 2 and upon which is mounted the bottom of an upright cylindrical shell or casing 3 carrying at its upper end a 25 horizontal shelf 4 which together with the base section 1 may form a part of the main supporting frame for the centrifugal drier and the tub or vat A of a clothes washing machine which is also circular and 30 preferably arranged in an upright position at one side of the casing 3 in substantially the same horizontal plane.

35 The cylindrical shell or casing 3 is closed at the bottom but open at the top to permit the insertion and removal of the wet clothes into and out of a rotary upright cylindrical container 5 which is rotatably mounted within the shell or casing 3 in a manner hereinafter described.

40 The top section 4 constitutes a drainage shelf which is preferably secured at one end to the upper portion of the periphery of the washing tub or vat A and is provided with a central cylindrical opening 6 of 45 substantially the same diameter as the interior diameter of the casing 3 and co-axial therewith, said shelf or section 4 being provided in its underside with an annular groove 7 in which the rim at the upper 50 end of the casing 3 is seated, or rather to permit the shelf 4 to be seated upon the upper marginal edge of the casing 3 to form a water-tight joint therewith.

55 A cover 8 is hinged at 9 to suitable lugs 10 on the top of the shelf 4 at one side of the opening 6 for vertical rocking movement to and from a position across the opening 6 and also to and from a position at one side thereof so as to permit the rotary 60 container 5 to readily pass through the opening 6 when the cover 8 is opened.

65 The cover 8 is provided with a handle 11 by which it may be manipulated and is also provided with a marginal horizontal flange 12 adapted to rest upon an annular

bearing on the upper face of the section 4 when the lid is closed, said lid being also provided with an annular vertical flange 12 adapted to engage the walls of the opening 6 when the cover is closed thereby cooperating with the flange 12 to form a substantially water-tight joint with the section 4.

An upright rock shaft 13 is journaled in suitable bearings 14 on the lower and upper sections 1 and 4 at the outside of the casing 3 and is provided with an operating member 15 adjacent the underside of the upper bearing 14 by which it may be turned in its bearings 14, the lower end of the rock shaft being provided with a crank arm 16 which may be connected by any suitable means to a clutch or other device for controlling the operation of the washing mechanism not shown, or for any other purpose to which it may be adapted.

The upper end of the rock shaft 13 extends above the bearing 14 and upon this extension is journaled a locking lever 17 adapted to be operated by hand into and out of engagement with a keeper 18 on the adjacent portion of the marginal flange 12 of the cover 8 for locking and releasing said cover in and from its closed position, said hand lever 17 being held against upward displacement by a nut 13' engaging the upper end of the rock shaft 13 and also serving to hold the shaft 13 against downward displacement.

The case 3 is provided with a central upwardly projecting post 19 co-axial therewith and having its upper end provided with a spherical end thrust bearing 20 adapted to engage in a semi-spherical seat 21 on the bottom of the container 5 for supporting the upper end of the container co-axially with the casing 3.

The container 5 is preferably cylindrical and of sufficiently less diameter than the casing 3 to form an intervening annular chamber 22 for receiving water which may be expelled from the clothes through the side walls of the container and permitting said water to collect in the bottom of the casing 3.

This rotary container is preferably closed at the bottom and open at the top and has side walls provided with perforations 23 through which the water from the wet clothes in the container may be expelled by centrifugal force as the container is rotated although it is evident that the side walls of the container may be substituted by any other porous material.

As shown in Figures 1 to 4 inclusive the cover 8 is provided with an upwardly projecting extension 24 having a gear chamber 25 and a motor chamber 26 arranged end to end horizontally and separated by an upright partition 27, said

chambers being provided with bottom walls which form portions of the top wall of the cover —8— to separate said chambers from the interior of the cover and outer casing —3—.

5 The gear chamber —25— extends entirely around the axis of the casing —3— and container —5— and is provided with a removable top closure —28— to permit access to the 10 interior thereof.

10 The motor chamber —26— is located at one side of the chamber —25— and is provided with a removable outer end closure —29— to permit access to the motor parts.

15 *Driving mechanism*

A motor —30— is mounted upon and within the chamber —26— and has its pole pieces —31— mounted directly upon the peripheral 20 walls of the adjacent portions of the case —26— while its armature shaft is journaled in suitable oil tight bearings —32— and —32'— in the partition —27— and outer end closure —29— respectively.

25 The outer end of the armature shaft is engaged with an end-thrust ball-bearing —33— which is held in place by an adjusting screw —34— in the outer end of the bearing —32'— as shown in Figure 4.

30 The inner end of the armature shaft extends through and beyond the partition —27— into the gear case —25— and is provided at its inner end with a bevel pinion —35— meshing with a relatively larger gear —36— which is secured to an upright shaft —37— co-axial with the axis of the outer casing —3— and rotary container —5— for transmitting rotary motion from the armature shaft to said container in a manner presently described.

35 A supplemental lid or closure —38— is rotatably mounted upon the underside of the cover —8— to move therewith into and out of frictional engagement with the upper marginal edge of the container —5— for opening and closing the top of said container as the cover —8— is opened and closed about the axis of its hinge pin —9—.

40 An upright tubular bushing —39— is tightly fitted in a suitable opening in the bottom of the gear chamber —25— co-axial with the casing —3— to extend some distance above and below the bottom of the gear chamber and is provided at its lower and upper 45 ends with anti-friction bearings —40— in which the lower and upper ends of the upright shaft —37— are journaled.

45 That is, the upper end of the bushing —39— is shouldered upon the upper surface 50 of the bottom of the gear chamber —25— to hold it against undue downward displacement while its lower end extends through a central opening in the closure —38— for a purpose presently described.

55 This closure —38— is journaled by means

of anti-friction bearings —41— upon the lower end of the tubular bushing —39— just below the cover —8— for relative rotation thereon, said bushing forming a part of the cover —8— and having its lower end threaded and engaged by a nut —42— which, in turn, serves to clamp the inner section of the anti-friction bearing —41— against the lower end of the hub of the cover —8— to hold the bearing in place and incidentally to hold the bushing —39— against accidental upward displacement.

60 An inverted cap section —43— is tightly fitted in a recess in the underside of the central portion of the closure —38— to extend across the lower end of the shaft —37—, bushing —39— and nut —42— for protecting the adjacent bearings from water or moisture from within the container —5—, said cap section being provided with one or more internal lugs —44— adapted to be engaged by a crank arm —45— which is secured to the lower end of the upright shaft —37— below the lower end of the bushing —39— and wholly within the cap section —43—.

65 This crank arm —45— and lug —44— on the cap section —43— constitutes a one-way drive connection between the upright shaft connection —37— and closure —38— for the container —5—.

70 The closure —38— constitutes a friction clutch member adapted to frictionally engage the upper end of the container —5— for transmitting rotary motion thereto as the cover section —38— is rotated and for this purpose the closure —38— is provided with an annular conical friction surface —46— movable into and out of engagement with the inner annular surface of the upper end of the container as the closure —38— is opened 100 and closed by the opening and closing movement of the cover —8—.

75 The cover section —8— and closure section —38— are sufficiently thin and resilient to compensate for any slight wear between the friction surface —46— of the section —38— and rim of the container —5— and thereby to assure driving connections between the rotating section —38— and container when, the sections —8— and —38— are in the closed position, it being understood that when these sections are opened the driving connection between the cover section —38— and container will be broken to allow the container to remain at rest or to be rotated by hand 115 independently of the closure —38— if desired as, for example, when transferring clothes to and from the container.

80 *Motor switch and brake control*

85 In machines of this character it is desirable to stop the operation of the motor and parts driven thereby as quickly as possible after the motor circuit has been broken by the opening of the suitable controlling switch 130

and also to release the motor and parts driven thereby at about the same time the motor switch is closed and for this purpose is provided a motor controlling switch —47— and a mechanical brake —48—, both of which are adapted to be controlled by a single operating lever —49— in a manner presently described.

The electric switch is mounted upon a suitable insulating block —50— within a suitable chamber —28— in the one side of the gear case —24— and comprises a relatively stationary terminal —51— and a self-opening resilient terminal —52— movable into and out of contact with the terminal —51—, said terminals being electrically connected in any well-known manner to the electric motor —30— for closing and opening the motor circuit.

The hand lever —49— is secured to one end of a cross shaft —53— which extends through and is journaled in opposite side walls of the gear case —24— and has its other end provided with a crank arm —54— for engaging and forcing the yielding terminal —52— into engagement with its companion terminal —51— when the lever —49— is rocked in one direction.

The brake —48— comprises a rotary friction disk —55— secured to and rotating with the inner end of the motor shaft as —30'— to cooperate with a non-rotatable friction plate —56— which is mounted upon diametrically opposite guide rods —57— on the partition —27— and normally spring-pressed toward the disk —55— by coiled springs —58— as shown in Figures 1 and 3.

A pair of bell crank levers —59— are mounted upon a supporting shaft —60— at opposite sides of the friction disk —55—, said bell-crank levers having depending arms —61— adapted to engage the outer face of the friction member —56— for moving said member out of engagement with the friction disk —55— against the action of the springs —58—.

The other arms as —61'— of the bell-crank levers —59— are adapted to be engaged by a pair of cams —62— on the shaft —53— so that the movement of the lever —49— and its cams —62— in one direction will disengage the clutch member —56— from its companion —55— against the action of the spring —58— or when the lever —49— is reversed the clutch member —56— will be forced into engagement with its companion —55— by the action of the spring —58—.

It will be observed that the switch operating arm —54— and cams —62— are mounted upon the same rock shaft —53— which is operated by the lever —49— and that they are relatively arranged to close the motor switch —47— simultaneously with the disengagement of the brake member —56— from its companion —55— and reversely to permit the opening of the switch —47— simultane-

ously with the engagement of the brake member —56— with its companion —55— thus assuring the stopping of the motor and parts actuated thereby immediately following the opening of the motor switch.

The construction shown in Figures 5, 6 and 7, except that the motor is placed in a vertical position and that its armature shaft is connected to the upright shaft for rotating the container by means of spur gears instead of bevel gears, otherwise responds substantially to the description previously given for Figures 1 to 4 inclusive.

It will also be observed that the cover —8— and closure —38— are provided with vertical vent openings —63— and —63'— respectively, the openings of each series being surrounded by upright flanges —64— and —64'—, the purpose of which is to not only allow the entrance of air into the interior of the container as the water is displaced from the center thereof toward the circumference to assist and expedite the drying of the clothes, but also permits the entrance of rinsing fluid through said opening into the clothes within the container —5— if desired to subject them to a rinsing operation.

Operation

When it is desired to use the machine for drying wet clothes the cover —8— carrying the closure —38— will first be fully opened after which the wet clothes are placed within the container —5— to any desired height or level within the length of said container after which the cover —8— with the closure —38— thereon is returned and locked in its closed position thereby bringing the closure —38— into frictional engagement with the upper end of the container —5—.

The lever —49— is then operated to close the motor switch —47— and to simultaneously disengage the brake disk —56— from its companion —55— against the action of the springs —58— thereby starting the motor and transmitting rotary motion to the container until practically all of the moisture is expelled therefrom by centrifugal force into the outer casing —3— which may be provided with any suitable drainage outlet, not shown, but commonly used in machines of this character.

After the short period of rotation of the container —5— with the clothes therein sufficient for drying the lever —49— may be reversed to permit the opening of the motor switch —52— and simultaneously release the brake member —56— which is then forced axially into frictional engagement with its companion disk —55— by means of the springs —58—, the latter being tensioned so as to produce a quick stopping of the motor and parts driven thereby including the container —5—.

When the rotating parts have ceased to revolve the lever —17— may be operated to release the cover —8— and allow it, together with the closure —38—, to be opened to permit the dried clothes to be removed by hand from the container —5— ready for a repetition of the operation previously described.

What I claim is:—

1. In a centrifugal clothes drying machine of the character described, an upright container for the clothes rotatable about a vertical axis and having an opening in its upper end for the passage of clothes therethrough, said container being of considerably less diameter than its vertical height to bring the center of the mass of clothes therein sufficiently close to the axis thereof to reduce to a minimum the vibration incidental to the rotation of the container and at the same time to maintain a relatively large capacity by its relatively greater height, and means for rotating said container, said container having a free and unobstructed opening from bottom to top and within the upright walls thereof, and a closure movable into and out of frictional engagement with the upper end of the container, said closure having a vertical opening surrounded by a vertical flange therethrough to permit the passage of air and rinsing fluid into the interior of the container when the closure is closed.

2. In a centrifugal clothes drying machine of the character described, a supporting frame having a top opening, a container rotatably supported within the frame and axially of the top opening, a cover for the frame opening hinged to one edge of the frame, a cover for the container rotatably mounted upon the frame cover and movable into and out of frictional engagement with the open upper edge of the container, a gear casing on the frame cover and a motor drive and gear train in the casing including a shaft extending from the casing and through the frame and container covers, and an arm and lug connection between the lower end of the shaft and container cover.

In witness whereof I have hereunto set my hand this 6th day of October, 1926.

PETER E. GELDHOF.
